UNITED STATES PATENT OFFICE.

HAZEN E. BALL, OF FREDA, MICHIGAN.

AUTOMATIC TRAIN-SIGNAL.

1,247,919.

Specification of Letters Patent. Patented Nov. 27, 1917.

Application filed December 4, 1916. Serial No. 134,999.

To all whom it may concern:

Be it known that I, HAZEN E. BALL, a citizen of the United States, residing at Freda, in the county of Houghton and State 5 of Michigan, have invented certain new and useful Improvements in Automatic Train-Signals, of which the following is a specification.

This invention relates to an improved 10 signal of the safety type and the principal object of the invention is to provide a signal which may be placed at a crossing and operated by a moving train to turn the signal to indicate that a train is approaching the crossing and to then release the signal and permit it to return to the normal position.

Another object of the invention is to so 15 construct this signal operating mechanism 20 that it may be carried by the tie supporting the rails and include a rod extending longitudinally of the track and move to a setting position through the medium of a rocker shaft, the rod being releasably held in a set 25 position by a trip moved to a releasing position by the wheels of the car.

Another object of the invention is to so 30 construct this signal that the indicating sign may be carried by a shaft mounted in a vertically extending casing and provided with a lever arm connected with the actuating rod of the track device.

Another object of the invention is to provide 35 a signal and actuating device which will be very simple in construction and easily installed.

This invention is illustrated in the accompanying drawings, wherein:-

Figure 1 is a top plan view showing the 40 signal in place,

Fig. 2 is an enlarged view showing the signal in elevation,

Fig. 3 is a view showing a fragment of the track device in elevation, and

Fig. 4 is a fragmentary sectional view 45 taken along the line 4—4 of Fig. 1.

The signal post or casing 10 is mounted adjacent the roadway indicated by dotted lines in Fig. 1 and carries a rotatable shaft 50 11 having a head or sign board 12 at its upper end positioned in the frame 13 carried by the signal post 10. A lever arm 14 extends from the lower end of this shaft 11 and is connected with a draw rod 15 so that 55 when the draw rod moves longitudinally, the shaft will be rotated in the casing 10.

It will thus be seen that under normal conditions the sign board or head 12 will extend as shown in Fig. 1 whereas when the actuating means is moved by the approaching train, the shaft 11 will be rotated to bring the sign board to the position shown in Fig. 2 in which position it may be easily read.

The actuating means includes a rod or 60 bar 16 extending along the ties 17 between the rails 18 and having one end connected with the bell crank lever 19 which bell crank lever is connected with the draw rod 15 for imparting movement to the draw rod as 65 the bar 16 is moved. This bar 16 is connected intermediate its length with the support or guide 18' and it is to be understood that as many of these supports 18 may be provided as necessary. A rocker shaft 20 is 70 journaled in the bearings 20' and is provided with a lever arm extension 21 connected with the bar 16. A turning or actuating lever extends from this rocker shaft 20 intermediate its length and is provided 75 with a head 23 for engagement by a suitable trip carried by the train and it will thus be seen that when the train approaches the road, the rocker shaft 20 will be rotated and the bar 16 moved longitudinally thus 80 imparting movement to the shaft 16 and setting the signal to a danger position. A spring 24 is connected with the actuating 85 lever 22 and with a base block 25 and serves to yieldably hold the rocker shaft in the position shown in Fig. 3 thus normally retaining the actuating bar 16 in a position to hold the signal at a safety position. A 90 latch 26 is pivotally mounted as shown at 27 and is yieldably held in a position to enter 95 the notch of the bar 16 by the spring 28, a bracing guide 29 being provided intermediate the length of this latch bar and a releasing trigger 30 extending beneath the outer end of the latch bar and adjacent one 100 of the rails so that when the train passes over the track, the signal will be first set to a danger position and after the warning has been given and the train is about to pass the road, one of the wheels of the cars will 105 engage the trip and move the same downwardly thus swinging the latch to a releasing position and permitting the spring 24 to return the actuating mechanism to its normal position and again set the signal at 110 a safety position. It will thus be seen that I have provided means for indicating that

a train is approaching a road crossing and have further provided a signal having a simple construction and an actuating means for turning the signal to a set position which is strong and durable and which can be easily constructed and set up in place. From an inspection of Fig. 1 it will be seen that this signal may be duplicated thus permitting the signals to be set when a train 10 is approaching from either direction.

What is claimed is:—

1. A signal comprising a carrier, indicating means carried by the carrier having a draw bar extending from the carrier, a rocker shaft rotatably mounted between the rails of a track and provided with a cam lever extending upwardly for engagement with an abutment carried by the train, means for yieldably holding the cam lever in a lowered position, a lever arm extending from the rocker shaft, an actuating bar extending longitudinally of the track and connected with the lever arm of the rocker shaft, a bell crank lever having one arm connected with the actuating bar and the second arm with the draw bar, and a latch positioned for engagement with the actuating bar to releasably hold the same in an adjusted position with the signal set, the latch being moved to a releasing position by a passing train to permit the actuating bars to return to the normal position.

2. A signal including a draw bar, and actuating means for the signal including a rocker shaft extending transversely of a track between the rails thereof, a cam lever extending from the rocker shaft, resilient means engaging the cam lever to yieldably hold the rocker shaft in a set position

with the cam lever lowered, a lever arm extending from the rocker shaft, an actuating bar slidably mounted and pivotally connected with the lever arm, a bell crank lever pivotally connected with the actuating bar and with the draw bar, and a latch for releasably holding the actuating bar in an adjusted position positioned in operative relation thereto.

3. A signal including a rotatably mounted indicator carrying shaft having a lever arm extending therefrom, a draw bar connected with the lever arm, and operating means actuated by a passing train including a slidable bar, a bell crank lever connecting the slidable bar with the draw bar, means actuated from a passing train for moving the sliding bar longitudinally in one direction as the train passes and yieldably held in an inoperative position for returning the sliding bar to its normal position after the train passes, a latch pivotally mounted and yieldably held in engagement with the sliding bar for engaging the same and releasably holding the same in a set position, and a trigger pivotally mounted and having one end engaging the latch and having the opposite end portion extended for engagement by the wheels of a train, the trigger when actuated by the train wheels moving the latch to release the sliding bar and permit the signal to return to its normal position.

In testimony whereof I affix my signature in presence of two witnesses.

HAZEN E. BALL.
